UNITED STATES PATENT OFFICE.

KNUTE E. ERICKSON, OF PORTLAND, OREGON.

DESIGN FOR A STREET-TRAFFIC SIGNAL.

Application filed January 9, 1926. Serial No. 16,016. Term of patent 3½ years.

To all whom it may concern:

Be it known that I, KNUTE E. ERICKSON, a citizen of the United States, residing at Portland, county of Multnomah, and State of Oregon, have invented a new, original, and ornamental Design for a Street-Traffic Signal, of which the following is a specification, reference being had to the accompanying drawing, forming a part thereof.

In the drawing:

Fig. 1 shows a perspective view of my street traffic signal.

Fig. 2 is an elevation thereof.

I claim:

The ornamental design for a street traffic signal as shown.

KNUTE E. ERICKSON.
